COOKING TOP

Claude E. Parker, Chicago, Ill., assignor to Gas Products Corporation, Chicago, Ill., a corporation of Illinois

Application March 16, 1940, Serial No. 324,293

9 Claims. (Cl. 126—39)

The invention relates to improvements in cooking tops for gas ranges or cook stoves. The present application discloses an apparatus constituting a species of the same generic invention, which is disclosed as embodied in a specifically different apparatus in my copending earlier filed application Serial No. 272,984 filed May 11, 1939, which in turn was copending with my still earlier filed applications Serial No. 84,880 filed June 12, 1936 and Serial No. 120,591 filed January 14, 1937 and Serial No. 235,961 filed October 20, 1938. These latter three applications also disclosed the broad aspects of the same invention here claimed, though illustrating it as embodied in specifically different forms of apparatus.

In cabinet type gas ranges it is desirable from the standpoint of appearance and cleanliness, to provide a substantially imperforate top plate or panel apertured only for the desired number of underlying burner heads. Maintenance of this top panel at a suitably low temperature to protect its porcelain or enamel finish and to prevent burning of a person touching it has, however, presented a serious problem.

Generally stated, one object of the present invention is to provide in a cooking top having a top panel, a novel arrangement for preventing overheating of such panel.

A more specific object is to provide in such a cooking top a novel arrangement for inducing cooling air to wash over the top of the panel and in effect insulate it from hot gases issuing laterally from beneath a utensil supported above the burner.

Another object is to provide in a cooking top of the type indicated a novel arrangement for supporting in the burner hole or holes of the top panel suitable burner heads together with heat confining and reflecting members coacting with the heads, the supporting arrangement being such as to insure automatically accurate centering of the parts in the burner holes and with respect to each other, the arrangement also being such, in accordance with a more specific object of the invention, as to minimize the direct conduction of heat from the parts noted to the top panel.

Further objects and advantages will become apparent as the following description proceeds, taken in connection with the accompanying drawings in which:

Figure 1 is a vertical sectional view, taken substantially along the line 1—1 in Fig. 2, of a cooking top structure embodying the invention.

Fig. 2 is a fragmentary plan view of the cooking top structure.

Fig. 3 is a vertical sectional view taken substantially along the line 3—3 in Fig. 2.

Fig. 4 is a fragmentary plan view of the cook-

ing top with the heat confining and reflecting member removed.

Fig. 5 is a detail sectional view taken substantially along the line 5—5 in Fig. 3.

While the invention is susceptible of various modifications and alternative constructions, I have shown in the drawings and will herein describe in detail the preferred embodiment, but it is to be understood that I do not intend to limit the invention by such disclosure but aim to cover all modifications and alternative arrangements falling within the spirit and scope of the invention as expressed in the appended claims.

15 In the exemplary construction 10 indicates a horizontal sheet metal top plate or panel for a gas cook stove. Desirably, this top plate has a glossy decorative finish of, for example, porcelain or enamel. In one aspect the present invention is concerned especially with a novel arrangement of parts for insuring maintenance of such a top plate at a sufficiently low temperature as to protect the finish and to prevent a person being burned by contact with the plate.

20 In the top plate 10 is a round burner aperture 11 bordered by a reenforcing flange 12 and centrally beneath which is located a gas burner head, designated generally by the numeral 14. The burner head may be of any suitable form for projecting flames upwardly beneath a utensil and has, in the present instance, been shown as being of the so-called round type with upwardly and laterally directed fuel emission ports 15 from which flames 16 issue beneath a utensil indicated generally at 16 in Fig. 1.

25 Also in the burner hole 11 is located a closure structure, embodying in the present instance a heat confining and reflecting member or hearth denoted generally by the numeral 17, and which 30 coacts with the head to substantially fill or close, from an appearance standpoint, the burner hole 11. The particular hearth 17 illustrated may be made of metal, for example, cast iron. It is of shallow dish or bowl shape and thus a top surface having a generally continuous annular portion of substantial lateral width encircling the apertured central portion of the hearth through which flames from the burner head 14 issue to lap the utensil 16.

35 Four radially extending utensil supporting arms 18 are disposed to seat the utensil 16 in closely spaced relation above the top of the hearth 17. In this way hot gases from the burner head 14 are confined between the opposed and fairly closely spaced faces of the hearth and utensil bottom and are directed laterally, finally escaping at the periphery of the utensil (see arrows in Fig. 1 indicating escape path of hot gases). The utensil 16 indicated is 40 of large size such as an ordinary skillet and be-

ing of, say, ten or twelve inch diameter extends beyond the edge of the opening 11 in the top panel so that the problem of preventing overheating of the top panel by the escaping hot gases is particularly aggravated.

To define an annular flue for an updraft of cooling air, the periphery of the hearth 17 is disposed in spaced relation to the encircling edge of the top plate aperture 11. Cooling air rises from the burner box beneath the hearth through the annular passage or flue 19 formed between the hearth and the flange 12, the width of the passage being such as to permit the flow of a substantial volume of air, such flow being at least in part induced by the entrainment effect of the hot gases issuing from beneath the utensil in the case of a large utensil like that shown.

A feature of primary importance which differentiates the present structure from, for example, that shown in my prior application Serial No. 272,984 referred to above, is the disposition of the peripheral rim 17^a of the hearth 17 in spaced relation above the plane of the top panel 10 (see Fig. 1). By virtue of this arrangement it is possible to achieve a substantial stratification of the air above the top panel. The cooling air rising through the flue 19 washes over the surface of the top panel in a lower stratum and the laterally flowing hot gases escaping from beneath the utensil are in a higher stratum. In this way a blanket of cooling air is interposed between the escaping hot gases and the adjacent surface of the top panel. In view of the fact that air is a relatively poor thermal conductor there is but little transfer of heat from the hot gases through the blanket of cooling air to the top plate. Consequently, the top plate is maintained at a suitably low temperature so that its finish is effectually protected and there is no danger of a person's being burned upon touching it.

The hearth 17 serves, in effect, as a barrier or baffle for splitting into two generally segregated streams the cool air rising from the burner box or space beneath the cooking top. At its outer edge the hearth coacts with the top panel to form the flue 18, as previously noted, for one of these streams of cooling air, the latter washing over the top panel as described. At its inner edge the hearth 17 is disposed in spaced relation to, and encircles, the burner head 14, thus defining a second annular flue 20 and through which rises a second stream or updraft of secondary air for the flames issuing from the burner head. Not only does the hearth 17 thus segregate and direct these two streams of air but it also thermally separates the cooling air stream through the flue 18 from the hot gases beneath the utensil.

To insure maintenance of the escaping hot gas well above the plane of the top panel it is requisite that the elevation of the utensil bottom and opposed barrier, in this case the hearth rim 17^a, be retained in preselected fixed relation with respect to the top panel. Such maintenance of fixed relation of these parts is desirably accomplished by mounting the hearth 17 and utensil seats 18 from the top panel itself. Furthermore it is desirable that the burner head 14 also be supported from the top panel and interlocked with the hearth so as to insure accurate centering of the head and hearth with respect to each other and to the burner hole 11, with the end in view of maintaining the annular flue spaces 19 and 20 with precision. On the other hand the connection of the hearth and burner head to the

top panel must not result in an undue heat transfer to the latter or the work of the air wash will be undone. To resolve the difficulty presented by these antithetical requirements a novel supporting arrangement for the hearth and head has been provided, such as to use the rising cooling air to cool the connections and minimize the transfer of heat to the top panel.

In the instant construction (see Fig. 4) the burner head 14 has a three point support. At its forward end a Venturi supply tube 21, which is rigid with the head, is removably connected to a control valve 22 in the usual manner, to form one point of support. The other two points of support are formed by two laterally extending integral arms 23 on the burner head. Flattened feet on the outer ends of these arms rest on lugs 24, which are integral with the top panel flange 12 and project into the hole 11. The outer ends of integral longitudinal reenforcing ribs 23^a, on the lower sides of the arms 23, are received in notches 24^a in the lugs 24, thus locating the head and restraining it against rotation or lateral displacement.

The hearth 17 is also supported on the lugs 24 as well as on an additional pair of lugs 25 (see Fig. 4), the latter, like the lugs 24, being integral with the lower edge of the top plate flange 12. The lugs 24, 25 are located at four equidistant spaced points about the burner hole 11. On the lower side of the hearth 17 is a pair of integral depending bosses 26 (Fig. 3) resting on the lugs 24 and a second pair 27 resting on the lugs 25. The bosses 26 are bifurcated at their lower ends to straddle the underlying ends of the arms 23 (Fig. 5). The bosses 27 are not so bifurcated but have projections 27^a on them received in complementary locating notches 25^a (see Figs. 3 and 4) in the lugs 25.

When the burner head 14 and member 17 are seated in the hole 11 on the proper lugs, as set forth, these parts 14, 17 are thus automatically centered in the hole so that their spacing relative to each other and to the flange 12 to define the flues 19, 20 is accurately determined. Moreover, since the utensil seating members 18 are fixed to the member 17, their height above the top panel 10 is accurately dimensioned as is the barrier edge 17^a between the top panel surface and the utensil seats. It should be particularly observed that the lugs 24, 25 and bosses 26, 27 are of comparatively small cross-sectional area, thereby minimizing the conduction of heat through them from the hearth 17 to the top panel. Also these connecting elements are located well below the zone of hot gases, which are confined above the hearth 17, and moreover, the connecting lugs and bosses are washed by cooling air rising through the flue 19 so that the direct conduction of heat from the hearth to the top panel is minimized.

I claim as my invention:

1. In a gas range cooking top, the combination with a generally flat sheet metal top plate having a burner opening in it, and a burner head located generally centrally beneath said opening, of a closure structure in said opening having a marginal portion spaced from the surrounding edge of the top plate opening and coacting with it to define a flue for an updraft of cooling air at the periphery of said opening, said structure also constituting a heat barrier preventing downward reflection of heat from the burner and being characterized particularly by the provision of an annular peripheral portion spaced above

the upper surface of said top plate so that hot gases escaping laterally from between a utensil overlying the unit and the top of said structure are directed over the top plate at a corresponding distance above it with a stratum of cooling air interposed between the top plate and such hot gases.

2. In a gas range cooking top, the combination of a horizontal top plate apertured for an underlying burner head, utensil seating means for supporting a utensil above the burner aperture and with the utensil bottom above the top plate, a hearth structure having an annular portion coacting with the edge of said aperture to define a flue for an updraft of cooling air at the margin of said aperture, said hearth structure also forming a barrier for directing hot gases issuing from beneath a utensil seated on said supporting means laterally above the top panel, and means including supporting lugs carried by the top plate and projecting into the aperture through said flue in position to be cooled by the cooling air in the latter for supporting said utensil seating means and said hearth in predetermined spaced relation with respect to the top plate.

3. In a gas range cooking top, the combination of a sheet metal top panel having an opening in it, lugs on said panel projecting into the opening, a burner head located generally centrally of the opening and having arms thereon with their ends seated on said lugs, and an independently removable closure structure in the opening also supported by said lugs and engaging with said arms so as to be held thereby in centered relation to the head.

4. In a gas range cooking top, the combination of a sheet metal top panel having an opening in it bordered by a downturned reinforcing flange, said flange having lugs thereon projecting into the opening at spaced points, a burner head located generally centrally of the opening, a heat confining structure presenting an upwardly facing heat reflecting surface and having a peripheral edge spaced from the edge of the opening and coacting with said flange to define a flue for an updraft of cooling air, said burner head having supporting arms thereon resting on said lugs, and said heat confining structure having projections beneath it also resting on said lugs for removably supporting said structure, said lugs and projections being disposed in the path of cooling air rising through said flue to minimize the conduction of heat to the top plate.

5. A gas cook stove comprising, in combination, a sheet metal top panel having an opening therein with a depending flange defining the edge of said opening, a burner head positioned centrally of said opening, a utensil supporting structure including an annular member having a plurality of utensil supports thereon, and means on the lower edge of said flange for supporting said member in inwardly spaced relation to the flange and with the upper edge of the member protruding above the plane of the top panel and forming a continuous protecting barrier preventing impingement upon the panel of hot gases discharged outwardly beneath the bottom of a utensil resting on said utensil supports and overlying the edge of said opening in the top panel, said utensil supports having seating surfaces disposed in a plane above said top panel.

6. A gas cook stove comprising, in combination, a sheet metal top panel having an opening therein with a vertical depending flange of substantial depth at the edge of the opening and a plurality of circumferentially spaced lugs at the lower edge of said flange, a burner head disposed centrally of said opening, and an annular heat reflecting member mounted upon said depending flange of the top panel with the burner head positioned centrally of said opening and said annular member extending laterally outward from the burner head to the edge of the opening, the lugs on said top panel flange projecting horizontally inward beneath said annular member and said member having depending portions at the periphery thereof removably seated upon said lugs.

7. A top structure for gaseous fuel cook stoves comprising, in combination, a top plate having an opening therein, a burner head positioned below and centrally of said opening and having fuel discharge means in its upper portion, a heat confining and utensil supporting structure, and means removably supporting said structure in said opening in the top plate comprising an annular member carried by the top plate, said structure including a heat barrier with one edge portion spaced horizontally outward from said fuel discharge means of the burner head and another edge portion spaced from said member to define an annular air passage opening at its lower side exteriorly of said barrier and at its upper side substantially in the plane of the top plate.

8. A top structure for gaseous fuel cook stoves comprising, in combination, a top plate having an opening therein, a burner head positioned below and centrally of said opening and having fuel discharge means in its upper portion, a heat confining and utensil supporting structure, and means removably supporting said structure in said opening in the top plate, said structure including a heat barrier having an upwardly facing inner edge portion encircling the burner so as to underlie the flames issuing from said fuel discharge means, and an outer edge portion over which the hot gases discharge so as to be heated thereby, said outer edge portion being spaced inwardly from the edge of said opening in the top plate to define an annular air passage opening at its lower side exteriorly of said barrier.

9. A top structure for gaseous fuel cook stoves comprising, in combination, a sheet metal top plate having an opening therein, a burner head positioned below and centrally of said opening and having fuel discharge means in its upper portion, a heat confining and utensil supporting structure, and means removably supporting said structure in said opening in the top plate comprising an annular depending flange bordering said opening, said structure including a heat barrier with one edge portion spaced horizontally outward from the fuel discharge means of the burner head and having another edge portion spaced from said flange to define an annular air passage opening at its lower side exteriorly of said barrier and discharging at its upper side above the top plate, and the supporting means for said structure further comprising circumferentially spaced elements disposed in the path of the air stream flowing through said passage.

CLAUDE E. PARKER.
